MINIATURIZED SPECTROPHOTOMETER

Paul A. Hoogesteger, Penfield, N.Y., assignor to
Bausch & Lomb Incorporated, Rochester, N.Y.

Filed Apr. 25, 1974, Ser. No. 464,006

Term of patent 14 years

Int. Cl. D10—04; D24—02
U.S. Cl. D32—2 C

FIG. 1

FIG. 2

FIG. 3

FIG. 4

FIG. 1 is a perspective view of a miniaturized spectrophotometer as viewed from the left front and embodying the principles of my new design;

FIG. 2 is a perspective view thereof as viewed from the left rear;

FIG. 3 is a view taken from the right side thereof; and

FIG. 4 is a bottom plan view thereof.

I claim:

The ornamental design for a miniaturized spectrophotometer, substantially as shown and described.
